UNITED STATES PATENT OFFICE

RUFUS E. BOSCHERT, OF SYRACUSE, NEW YORK

FLUID-PRESSURE-OPERATED MOTOR

Application filed July 14, 1926. Serial No. 122,301.

This invention relates to a press, preferably of the upright type, having a stationary ram and a movable cylinder cooperating with the ram and adapted to be operated by any fluid pressure such as water, steam or compressed air to be used as the motive power for actuating the movable pressing element through the medium of toggles or knuckle joints and suitable connections between the knuckle joints 10 and cylinder.

The main object is to construct and assemble the various parts of the press in such manner that they may be brought into more compact relation than has heretofore been 15 practised and at the same time to greatly increase the power of operation of the movable pressing element with a given fluid pressure and head area of the ram and cylinder.

In other words, I have sought to materially 20 increase the efficiency of the press by anchoring the ram directly to the frame and reciprocating the cylinder relatively thereto through the medium of fluid pressure and retracting means, acting directly upon the cylinder in reverse directions.

One of the specific objects is to locate the center of the toggles as nearly as possible in a direct line with the axis of the ram and cylinder and to connect the toggle joint with the 30 cylinder in approximately the horizontal plane of said axis so that the action of the cylinder under fluid pressure may exert a direct pull upon the toggle joints when the toggles are approaching a straightened position for 35 forcing the movable pressing element into pressing co-action with the upper pressing element upon the work.

Another broad object is to balance as nearly 40 as possible the strains or stresses upon the various operating parts and thereby to reduce excessive lateral thrusts and incidental wear of those parts.

A further object is to provide means whereby 45 the upper pressing element may be easily and quickly adjusted toward and from the movable pressing element to conform to the thickness of the work operated upon. Another object is to provide means for limiting 50 the movement of the cylinder in either di-

rection and thereby to vary the rectilinear movement of the movable pressing element.

Another object is to provide a stop for limiting the pressing action of the toggles to or toward a substantially straightened position. 55 Other objects and uses relating to specific parts of the device will be brought out in the following description.

In the drawings:

Figure 1 is a top plan of a fluid-operated 60 press embodying the various features of my invention.

Figure 2 is a longitudinal vertical sectional view taken on line 2—2, Figure 1.

Figure 3 is a transverse vertical sectional 65 view taken on line 3—3, Figure 1.

Figure 4 is a horizontal sectional view taken in the plane of line 4—4, Figure 2.

The main supporting frame of the press comprises a base —1—, a press head —5—, 70 strain rods —7— and upright beams or standards —2— which are rigidly attached to the base —1— by bolts —3— to extend upwardly therefrom and to which the head —5— is adjustably secured by a cross-bar —6— and 75 clamping bolts —6'—. These standards serve as a support for a fluid-pressure-operated motor hereinafter described.

The base —1— is substantially rectangular in top plan and is provided near its four 80 corners with upwardly extending strain rods —7— for supporting the upper press head —5— and an underlying vertically movable platen —8—, both of which are located in front of the upright standards —2—. 85

The base —1—, head —5— and platen —8— may be made of cast metal or other suitable material, while the upright standards —2— are preferably made in the form of I-beams of steel having their flat sides facing forwardly and rearwardly and substantially straight and parallel. 90

The adjacent faces of the pressing elements —5— and —8— are provided with 95 suitable hollow plates —5'— and —8'— which may be heated by steam, gas or electricity, and together with interposed layers —5''— and —8''— of asbestos insulation or its equivalent, are bolted or otherwise secured to their re- 100

spective pressing elements between the strain rods —7—.

These pressing elements —5— and —8— are also rectangular in top plan and are provided near their corners with vertically aligned openings therethrough for receiving the strain rods —7— which guide the platen —8— against lateral displacement.

The upper ends of these strain rods are threaded and are engaged by lower and upper nuts —9— and —10—, which in turn, engage respectively the lower and upper faces of the upper pressing head —5— for permitting vertical adjustment of said head and for holding it in its adjusted position.

The upper nuts —10— are preferably provided with sprocket teeth —11— adapted to be engaged by a sprocket chain belt —12'— whereby the rotation of the hand-wheel 20 —12— will effect a corresponding rotation of all the nuts —10— for adjusting the head —5—.

The lower pressing element —8— is supported by front and rear sets of toggles 25 —13— and —13'— having their lower links pivotally connected at —14— to the base —1— and their upper ends pivotally connected at —15— to the underside of the movable pressing element —8—, while the adjacent ends of each toggle joint are pivotally connected to each other by bolts —16—.

These toggles are disposed between the upper face of the base —1— and lower face of the pressing element —8—, while the pivots 35 —14— and —15— of each toggle are disposed in the same vertical plane parallel with the standards —2— so that the knuckle joints which are substantially midway between the pivots —14— and —15— are free to flex forwardly and rearwardly toward and from straightened positions, as indicated by dotted lines in Figure 2.

The flexing joints or knuckles of the front and rear sets of toggles are connected by links 45 —17— whereby both toggles are caused to flex in the same direction simultaneously, thus preserving the alignment of the moving pressing element —8— parallel with the pressing element —5—.

50 Motive power

Suitable fluid-pressure operated means is provided for flexing the toggles toward a straightened position against the action of any 55 suitable retracting means, and for this purpose a hollow cylindrical piston or ram —18— is rigidly secured by bolts —19— or equivalent fastening means to the rear upright faces of the standards —2— to extend rearwardly 60 therefrom with its axis in substantially the same horizontal plane as the center of the toggle joints when moved to a straightened position, the rear end of the ram being closed except for the reception of one end of the supply pipe —20— for the entrance and exit of

the pressure fluid. A cylinder —21— is slideable axially along and upon the periphery of the ram —18— and is provided at its front end with a suitable gland and packing —22— to form a fluid-tight joint with said ram, the outer end of the cylinder being closed to receive impact of the inflowing motive fluid under pressure.

The cylinder —21— is provided with a pair of apertured lugs —23— projecting laterally 75 from opposite sides thereof for receiving adjustable bolts —24— which are movable axially in said lugs and held in operative position by lock nuts —25—, Figure 4, engaging the rear faces of the lugs.

The front ends of the bolts —24— in front of the lugs —23— are bifurcated for receiving the adjacent ends of a pair of links or connecting rods —26— which extend along opposite sides of the cylinder —21— and ram —18— and have their front ends connected to the knuckle joint pivotal bolt —16— of the rear set of toggles —13'— as shown in Figure 4 while the rear ends of the rods are pivotally connected at —27— to the front ends of the bolts —24— thereby establishing positive connection between the cylinder —21— and toggles —13'— and through the medium of the links —17— with the toggles —13— whereby the longitudinal movement of the cylinder —21— upon the ram —18— will be transmitted to the lower pressing element —8— for moving the latter toward and from the press head —5—.

The connecting rod —26— and bolts —24— 100 are disposed in approximately the same horizontal plane as the axis of the ram —18— and cylinder —21— so as to exert a direct pull upon the knuckle joints of the toggles —13— and —13'— as the cylinder —21— is forced 105 outwardly by the motive fluid.

Retracting springs —29— are preferably located in planes below and above the ram —18— and cylinder —21— or in the vertical plane of the axis of said ram and cylinder 110 and have their front ends attached by suitable bolts —30— to adjacent cross bars —31— which are secured to the rear flanges of the upright standards —2—, the rear ends of the springs being connected to eye bolts —32— 115 which, in turn, are adjustably mounted in apertured lugs —33— on the outer end of the cylinder —21—, said bolts being provided with nuts —34— engaging the outer ends of the bolts to permit the adjustment of the tension of the springs —29— as may be required to expedite the return of the cylinder following each pressing operation.

The lower lug —33— on the outer end of the cylinder —21— is provided with a shoe —35— 125 which is slideable along and upon a rearwardly projecting guide beam —36— having its forward end rigidly secured to a cross bar —37— on the lower ends of the upright standards —2— and its rear end carried by a supporting 130

leg —38— which may rest upon the same support as the base —1—, said guide beam —36— being directly below the axis of the ram —18— and cylinder —21— and parallel therewith for additionally supporting and guiding the cylinder in its reciprocating movement.

A cross bar —39— is secured to the front faces of the upright standards —2— in the horizontal plane of the axis of the ram —18— and cylinder —21— to form an abutment adapted to be engaged by one or more stop washers —40— of suitable thickness on the front ends of the connecting rods —26— to limit the rearward movement of the cylinder and also to limit the movement of the toggle knuckles toward a straightened position as may be desired to regulate or limit the closing movement of the movable pressing element, so that with the same pressure in the cylinder the pressure applied to the material under pressure can be varied according to the stopping position of the toggles and cylinder, and by means of washers or other devices the forward movement of the cylinder —21— on the ram —18— may be varied and thereby the vertical movement of the pressing member —8— can be made more or less to give any desired opening between the pressing members.

The pipe —20— for the motive fluid may be connected to any available source of supply of steam, compressed air or liquid under pressure and is provided with a controlling valve —20'— operable at will, and, if desired, may be of the two-way type, one way for admitting the motive fluid and the other way for exhausting the fluid from the cylinder during its return by the retracting means.

A press constructed in the manner described is particularly simple, strong and durable and is adapted to be installed in compact space and easily controlled and is capable of producing exceedingly high pressure by reason of the toggle action and the direct connection between the movable cylinder and knuckle joints of the toggle.

What I claim is:—

1. A fluid-pressure operated motor comprising a hollow stationary ram having its outer end open and its inner end provided with a transverse wall, a cylinder reciprocally movable along and upon the periphery of the inner end of the ram and spring-pressed toward the open end of the ram and its outer end closed to form a chamber between its closed end and the transverse end of the ram, and means for introducing fluid under pressure through said end wall and into said chamber for moving the cylinder in the opposite direction.

2. The combination with an upright support having a horizontal guide extending laterally therefrom, of a stationary ram secured at one end to said support and extending laterally therefrom in the direction

of extension of and in a plane above the guide, a cylinder reciprocally movable along and upon the periphery of the other end of the ram and also along and upon the guides and having its outer end closed and cooperating with the adjacent end of the ram to form a chamber, means for introducing fluid under pressure through the ram and into said chamber for operating the cylinder in one direction, and means for returning the cylinder.

In witness whereof I have hereunto set my hand this 9th day of July, 1926.
